(57) **CLAIM**

The ornamental design for an implantation tool as shown and described.

DESCRIPTION

FIG. 1 is a first top perspective view of an embodiment of an implantation tool, showing my/our new design;

FIG. 2 is a second top perspective view of the implantation tool of FIG. 1;

FIG. 3 is a bottom perspective view of the implantation tool of FIG. 1;

FIG. 4 is a left elevational view of the implantation tool of FIG. 1;

FIG. 5 is a right elevational view of the implantation tool of FIG. 1;

FIG. 6 is a front elevational view of the implantation tool of FIG. 1;

FIG. 7 is a back elevational view of the implantation tool of FIG. 1;

FIG. 8 is a top plan view of the implantation tool of FIG. 1; and,

FIG. 9 is a bottom plan view of the implantation tool of FIG. 1.

The broken lines shown in the drawings represent features of the implantation tool that form no part of the claimed design.
